LOCK

**William George Banham, Edmonton, Alberta,
Canada**

Application February 29, 1952, Serial No. 274,204

3 Claims. (Cl. 292—202)

1

My present invention relates to improvements in a lock and especially to one in which the latch has two locking positions for selectively engaging either of two relatively movable spaced elements.

An object of the invention is to provide a two-way lock designed to selectively hold either one element against lateral movement or another element against vertical movement relative to the lock carrier.

A further object of the invention is to provide a mortise lock selectively engageable with either of two spaced elements to hold the one and free the other, such spaced elements when free being movable in planes at right angles to each other.

A further object of the invention is to provide a mortise lock insertable flush in the edge of a carrier element and having a latch movable into either of two sockets alignable respectively on opposite sides thereof to prevent either the transverse movement of one of said sockets or any but limited vertical movement in one direction of the other socket.

A further object of the invention is to provide a lock having a latch engageable with either of two sockets, such latch being self-locking against displacement in one of said sockets on the relative movement of the latch and socket in one direction and being ejected from the socket on the relative movement of the parts in the reverse direction, on which ejection the latch may be caused to seat in the other socket.

A still further object of the invention is the provision of a novel, efficient and highly useful lock of the nature specified that is characterized by structural simplicity, its ease of installation, dependable operation and low cost of production whereby the same is rendered commercially desirable.

To the accomplishment of these and related objects as shall become apparent as the description proceeds, the invention resides in the construction, combination and arrangement of parts as shall be hereinafter more fully described, illustrated in the accompanying drawings, and pointed out in the claims hereunto appended.

The invention will be best understood and can be more clearly described when reference is had to the drawings forming a part of this disclosure wherein like characters indicate like parts throughout the several views.

In the drawings:

Figure 1 is a perspective view of the lock with the two spaced selectively-engageable sockets both aligned therewith;

Figure 2 is an elevation thereof with the latch

2

engaged in the relatively vertically movable socket:

Figure 3 is a corresponding side elevational view, with parts shown in section; and

5 Figure 4 is an elevation of a portion of a hinging double hung sliding window, showing a possible installation of this lock.

10 While useable in any assembly where parts are to have relative sliding and swinging movements, I have shown this instant lock applied to a hinging double hung sliding window in Figure 4, only for the purpose of illustration and the orienting of the three principal and individually separable parts thereof. In this window structure the sash A has a double stile or side rail B at each side slideable in the usual guide channels C of the frame D. The sash part of the stile is connected to the outer stile post by a pivot E near the bottom to allow the sash to be hinged inwards but is held in normal position by the lock F set in the top of the stile. When it is desired to swing the window in, the stile lock is released from the sash A and moved to engage a socket G in the frame D to prevent

25 the upward sliding of the stile post, thereby causing the sash to be supported horizontally on the sill, as for cleaning. Thus it will be seen that the latch part of the lock is mounted in the top of the stile post and is selectively caused to engage spaced and alignable sockets in either the laterally swinging sash A or the relatively vertically movable frame D to free the one and hold

the other. In the instant lock the latch consists of a relatively thin flat plate 1 of irregular shape rounded at the end 2 and having its underside 3 provided with a step 4 thence tapering to meet the straight or flat top 5 at a point 6, the top 5 joining the rounded end 2 by an angularly disposed end 7. The latch 1 is mounted in an open

posed end 1. The latch 1 is mounted in an open ended U-shaped pocket 8, the vertically disposed arms 9 of which have an exterior flange 10 at the top, and transversely through which pocket a terminally threaded pivot pin 11 extends, being accommodated by a bore 12 in the latch 1 concentric with the rounded end 2.

40 A pair of sockets each individually alignable with and movable relative to the latch 1 lie one on each side of the pocket 8. These sockets are adapted to be mounted on carrier elements movable in planes at right angles to one another, e. g., the one to move laterally across the end of the latch pocket and the other to slide vertically by the opposite open end of the pocket, and each of said sockets is capable of receiving the swing-
50 ing pivot carried latch plate.

Designed to be mounted with its top at the same

horizontal level as the pocket 8, the first socket is a channel-like member 14 alignable longitudinally with the pocket 8 as seen in Figures 1, 2 and 3, being of substantially the same width as the pocket and having similar exterior top flanges 15, however the bottom 16 of the channel is inclined to serve as a rest for the latch 1 when nested therein and to support the latch's top edge 5 horizontal and preferably flush with the top flanged edges 15 and 10 of the channel and pocket respectively. In such nested position it is desirable that the latch be so proportioned that its pointed free end 6 project slightly beyond the channel socket 14 to afford a thumb grip whereby said latch may be raised clear of said channel socket.

The second socket in vertically slidable relation to the latch is a vertically elongated mortise-type housing 17, the latch-confronting face 18 thereof suitably perforated as at 19 for attaching screws, having a long thin slot 20 therein. At its upper end this slot 20 ends short of the top of the housing 17 by a distance greater than the length of the latch from the shoulder 4 to its pointed end 6 so that the latch 1 when swung into said socket housing 17 through the admitting slot 20 is held against dislodgement by the end 6 being trapped therein by the front plate overhanging lip 21 at the top of the slot that rests on the latch shoulder 4 that serves as a stop barring further vertical movement between the latch and socket housing in one direction. On the reverse relative movement of these parts, however, the face plate 18 at the lower end of the slot 20 engages the inclined end 7 of the latch 1 and rotates it in an ejecting movement to throw it back into the channel socket 14.

Applied to the window structure shown in Figure 4 and hereinbefore described, the latch pocket 8 is recessed in the top of the outer part of the stile B, the channel socket 14 similarly recessed in the top of the inner rail part of the sash A at the edge thereof and the mortise housing 17 is set into the bottom of the guide channel C of the frame D at the normal level of the top of the sash. Thus, for the usual sliding of the sash in normal use, the latch 1 lies horizontally extended in the channel 14 securing the sash against hinging inwards on the stile connecting pivots E but when it is desired to swing the sash A inwards as for washing the outside of the window, the latch 1 is raised clear of the channel 14 and rotated into the mortise housing 17 allowing only a very limited vertical lift to the outer stile post until the shoulder stop 4 of the latch strikes the lip 21 at the top of the slot 20, thereby supporting the inwardly hinged sash in horizontal position as it rests on the window sill. To reset the window, the sash is hinged upwards into its normal planar position with the channel 14 aligned with the latch pocket 8 in the top of the outer stile post, then the whole sash pressed down slightly so that the trapped tip of latch is first cleared of the lip 21, then the tapered bottom 7 thereof engages the bottom of the slot 20 and the latch 1 is thrown clear of the socket housing 17 and into the channel 14, again locking the sash and outer stile part against lateral separation.

Thus it will be seen that a new and highly useful two-way lock is provided wherein a rotatable flat plate latch is individually engageable with

either of two spaced members movable in directions at right angles to one another to lock them against relative lateral and vertical movements respectively, and while it has been shown and described as applicable to a specific window structure, it will be manifest that such a lock is capable of widely varying uses and many different embodiments within the scope of the appended claims without departing from the spirit or scope thereof, and it will consequently be apparent that all matters contained in the foregoing shall be interpreted as illustrative and not in a limitative or restrictive sense.

What I claim as new and desire to secure by Letters Patent is:

1. A lock comprising a U-shaped pocket open at the top and both ends, a latch swingingly mounted in said pocket on a transverse pivot, a channel member open at the top and ends and movable laterally with respect to said latch and alignable therewith to receive the same and a vertically elongated socket member on the opposite side of said latch from said channel member and slidable in relation to said latch in which said latch may engage when freed from said channel; said latch being a relatively thin flat plate having a short angularly extending end running upwards from near said pivot, a straight flat normally horizontal top and a sloping underside having a step therein and therebeyond tapering to meet said flat top at a point, whereby when said pocket and said channel member are aligned and said latch is seated in the latter, the straight flat top of said latch lies flush with the tops of said pocket and channel member.

2. A lock as set forth in claim 1 wherein the length of the latch plate from said pivot to its pointed end, relative to the length of said pocket and said channel member, is such that the pointed free end of said latch plate projects beyond the remote end of the channel member, providing a thumb lift to disengage said latch from said channel member.

3. A lock as set forth in claim 1 wherein said socket member is a mortise-type housing with a slot in the latch-confronting face thereof through which said latch plate may enter, the sliding of said socket member in one direction bringing the top of the slot against the step in the sloping underside of the latch and in the opposite direction causing engagement of the short angularly extending end of the latch plate and the bottom of said slot to eject the latch plate; said latch plate when standing vertically in said socket member resting with its flat top against the inside of said housing and when ejected therefrom falling into said channel member to lie horizontally with its flat top flush with the top of said channel member.

WILLIAM GEORGE BANHAM.
